UNITED STATES PATENT OFFICE.

DAVID N. LENNOX, OF GREENOCK, SCOTLAND.

MACHINE FOR INKING AND REINKING TYPE-WRITER AND SIMILAR RIBBONS.

977,661.

Specification of Letters Patent. Patented Dec. 6, 1910.

Application filed March 27, 1908, Serial No. 423,755. Renewed May 12, 1910. Serial No. 560,981.

To all whom it may concern:

Be it known that I, DAVID NEIL LENNOX, a subject of the King of Great Britain, residing at Greenock, Scotland, have invented 5 certain new and useful Improvements in Machines for Inking and Reinking Type-Writer and Similar Ribbons; and I do hereby declare the following to be a full, clear, and exact description of the invention, such 10 as will enable others skilled in the art to which it appertains to make and use the same.

This invention relates to a machine designed for use in inking and reinking type- 15 writer and similar ribbons.

In carrying out my invention, I have in view the provision of an extremely simple construction of machine for this purpose and one which may be used by any one for the 20 purpose of reinking typewriter ribbons at a much lower cost than would be involved in the purchase of a new ribbon.

More specifically, the novelty in my invention resides in the provision of an expressing 25 roller which coöperates with the inking roller of the machine to express surplus ink from the ribbon being treated and in the novel means devised by me for so adjusting this expressing roller that it will bear more 30 or less firmly in the direction of the inking roller, this construction permitting of the ribbon being supplied with just the proper amount of ink.

Another novel feature of the invention re- 35 sides in the manner of mounting the ink well or container, in which the inking roller is partly rotatable, so that it may be readily removed when it is desired to clean it or to replenish it with ink.

In the accompanying drawings, Figure 1 40 is a side elevation of the machine embodied in my invention, Fig. 2 is a similar view of the opposite side thereof, Fig. 3 is a vertical longitudinal sectional view through the 45 machine, Fig. 4 is a vertical transverse sectional view, Fig. 5 is a horizontal sectional view taken in a plane with the bearings for the expressing roller of the machine; and, Fig. 6 is a similar view but taken below the 50 bearings of the ribbon rolls or spools.

As shown in the drawings, the machine 55 comprises a base 10 which may be of wood or of metal as may be desired and sides 11 which extend vertically from the base in spaced parallel relation and adjacent the side or longitudinal edge of the said base,

the said sides being connected at their upper ends by means of a cross piece 12 which may be integral with the said ends of the sides or separate therefrom and secured thereto. The ribbon spools of the machine are indicated by the numeral 13 and these spools are journaled by means of suitable trunnions 14 which they carry at their sides, between the sides 11 to each side of the 65 transverse middle of the machine. These spools may be of any desired size, both as regards width and diameter and may include any desired or conventional means for the attachment of the ends of the ribbon to 70 be inked, thereto. Between these spools 13, the sides 11 of the frame of the machine are cut away to form openings 15 through either of which a semi-cylindrical ink container 16 may be inserted into position between the said sides, the container being 75 formed upon each of its sides with a pair of pins or studs 16' which project laterally. The studs 16' upon one side of the ink container are inserted in openings 17 formed in one side 11 of the frame of the machine 80 and the pins 16' at the other side of the container are positioned against the under edge of the opening 15 in the other side of the frame, one to each side of a projection 18 formed at the said edge of the opening and pivoted latch hooks 19, carried by the said side of the frame, are engaged with these 85 last mentioned pins and serve to support the corresponding sides of the ink container. 90

A vertically extending slot 20 is formed in each side 11 of the frame of the machine in a plane mid-way between the peripheries of the ribbon spools 13 and seated in each of these slots and resting at the lower end thereof, is a bearing block 21, the said blocks being formed at their side edges with flanges 22, the side edges of the slots being received between the flanges at the side edges of the corresponding blocks 21, the blocks being held in this manner against accidental disengagement or displacement from the slots. An inking roller 23 is formed at its ends with trunnion 24 which are journaled in the bearing blocks 21 and this roller is located partly within the ink container 16 so as to gather ink therefrom and apply it to the ribbon to be inked as will be presently made apparent, the ribbon being wound upon one of the rollers 13 from the other roller, passing over the said inking roller 23. Bearing blocks 25 which

are similar in construction to the blocks 21 except that they are of greater height, are also mounted in the slots 20 in the sides of the frame of the machine and journaled in these last mentioned bearing blocks 25 are 5 trunnions 26 at the ends of an expressing roller 27, the said expressing roller 27 being journaled in this manner directly above the inking roller 23 and the ribbon to be inked, 10 which is indicated by the reference character A, being passed as stated, over the inking roller 23 and between this roller and the expressing roller 27.

It will be understood of course that the 15 bearing blocks 25 are slideable vertically in the slots 20. An adjusting screw 28 is threaded through a threaded opening 29 formed at the middle of the cross piece 12 of the frame of the machine and the lower 20 end of this adjusting screw is swiveled to a leaf spring 30 midway of the ends of the same, the leaf spring having its end bearing against the upper ends of the block 25. The 25 tendency of this spring 30 is, of course, to force the bearings 25 in a downward direction and in doing this, the spring serves to hold the expressing roller 27 with a greater or less degree of firmness, against the inking roller 23 or, when the machine is in operation, 30 against the ribbon which is trained over this roller 23, the surplus ink taken up by the ribbon from the inking roller 23, being expressed and in this manner removed by the expressing roller 27, it being understood 35 that the tension of the spring 30 may be adjusted by adjusting the screw 28 and consequently the expressing roller may be made to bear with greater or less pressure upon the roller 23, the amount of ink taken 40 up and absorbed by the ribbon being in this manner regulated.

Fixed upon one of the trunnions 14 for each of the ribbon spools is a balanced handle 31, these handles serving as a means whereby 45 the spools may be rotated to unwind the ribbon from one spool and wind it upon the other spool. A similar handle 32 is fixed to one of the trunnions 26 for the expressing roller 27 and this handle is used under conditions which will be presently explained. 50 A leaf spring 33 is fixed to the inner face of each of the sides 11 of the frame of the machine adjacent each end thereof and these springs are bent to extend outwardly and to 55 bear against the adjacent end faces of the rotatable ribbon spools 13, the spring acting to prevent racing of the spools or in other words to limit their freedom of movement so that one spool will not unwind a surplus of 60 ribbon while the other spool is performing the winding operation.

The operation of the machine embodied in my invention is as follows:—The ribbon to be inked is first wound upon one of the 65 spools 13 and the free end of the ribbon is

then inserted between the inking roller and the expressing roller, the handle 32 for the expressing roller being then rotated so as to receive the ribbon between the two rollers, the ribbon being then connected at its said end to the other spool 13 and the last mentioned spool rotated to wind the ribbon thereon and to unwind it from the first mentioned spool 13. It will be understood in connection with the above description and 70 from the drawings that the expressing roller may be brought to bear with a greater or less degree of firmness against the inking roller and that consequently the machine may be adapted to apply a greater or less quantity 80 of ink to the ribbon to be treated, the ribbon absorbing less ink as the expressing roller is brought to bear with considerable firmness against the inking roller.

It will be understood that I am not to be 85 limited to the particular material in manufacturing any of the elements of the machine and particularly the inking and expressing rollers. These rollers may be made of metal 90 with a wooden shell or sleeve or may be made of metal or wood with a rubber or guttapercha covering or they may be made of wood or metal and provided with an absorbent covering of any desired material.

What is claimed, is:—

1. A machine of the class described comprising a frame including sides, rotatable ribbon spools mounted in the frame, an inking roller journaled in the frame, an expressing roller mounted in the frame in operative 100 relation with respect to the inking roller, one of the sides of the frame being formed with openings, latches fixed at the other side of the frame, an ink container within which the inking roller is partly rotatable, and pins 105 projecting laterally from each side of the ink container, the pins at one side of the ink container being inserted in the openings in the said side of the frame, and the pins at the other side of the ink container being engaged 110 by the latches.

2. In a device of the kind described, a pair of standards, an inking roll revolvably supported in said standards, bearings slidably mounted in said standards, an expressing roll 115 revolvably supported in said bearings, a cross bar connecting said standards, a tension screw held in said cross bar and provided at its lower end with a ball projection, and a leaf spring bearing at its ends on the expressing roll bearings and connected to said spring by a socket arranged to form in connection with the ball of the tension screw a ball and socket joint.

In testimony whereof, I affix my signature, in presence of two witnesses.

DAVID N. LENNOX.
